UNITED STATES PATENT OFFICE.

GUSTAVE W. TREICHEL, OF CHESTNUT HILL, PENNSYLVANIA.

PUZZLE.

SPECIFICATION forming part of Letters Patent No. 692,559, dated February 4, 1902.

Application filed April 23, 1901. Serial No. 57,061. (No model.)

To all whom it may concern:

Be it known that I, GUSTAVE W. TREICHEL, a citizen of the United States, residing at Chestnut Hill, county of Philadelphia, and State of Pennsylvania, have invented a certain new and amusing Puzzle, of which the following is a specification.

My invention relates to a new and amusing puzzle; and it consists of three parts, one large part and two small ones, the smaller parts being connected to the larger part by a string or other flexible connection, and the object of the puzzle is to remove the two smaller parts and the string from the larger part, which can be done by proper manipulation.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 represents a front elevation of the puzzle, showing the same in its normal position. Fig. 2 is a perspective view showing the position the puzzle would be placed in to separate the larger part from the smaller one, and Fig. 3 is a vertical section while it is in the same position as Fig. 2.

In carrying out my invention as here embodied, A represents a flexible piece of leather or similar material, which may be of any desired configuration, but preferably heart shape.

B is a strip which is formed by making two slits longitudinally of the piece A, and thus the strip B will be joined to the body A at both ends. Directly below the strip B a hole C is formed through the body A.

D are two flat pieces of stiff material—such as metal, celluloid, or the like—and they may be made of any desired configuration, but are also preferably made heart shape. These pieces D are secured to each end of the

string E. The loop of this string passes through the hole C and then around the strip B, as shown in Fig. 1, and the object of the puzzle is to separate the string to which the two pieces D are secured from the larger part A without cutting the string or untying any knots. To do this it is only necessary to make a loop of the strip B and force this loop through the hole C from the rear to the front, and after this loop C is through the hole the string can be pulled, so that the loop of the string will come within the loop of the strip B, as shown in Figs. 2 and 3, and then it is very easy to pull one of the smaller pieces D through the loop in the strip B, and thus remove the string from the body A.

This puzzle can be all stamped out, and thus made very cheap, while at the same time making a very amusing and entertaining toy.

Of course I do not wish to be limited to the exact construction here shown, as slight modifications could be made without departing from the spirit of my invention.

Having thus fully described my invention, what I claim is—

A puzzle consisting of three parts, one large part and two smaller parts, the large part to be made of flexible material, the smaller parts to be made of stiffened material, two vertical slits cut through the larger part parallel with one another, these slits terminating before the edge of the part cut through is reached so as to form a strip between the two slits, a hole formed through the flexible piece directly beneath the strip, a string, the loop of which is adapted to pass through said hole from the front to the rear and then around the strip, the two stiffened smaller parts adapted to be secured to each end of the string, substantially as described and for the purpose specified.

In testimony whereof I have hereunto affixed my signature in the presence of two subscribing witnesses.

GUSTAVE W. TREICHEL.
